Primary Examiner — Bridget L Eland

(57) **CLAIM**

The ornamental design for a mobile phone, as shown and described.

DESCRIPTION

FIG. 1 is a front perspective view of a first embodiment of a mobile phone, showing our new design;
 FIG. 2 is a front view thereof;
 FIG. 3 is a back view thereof;
 FIG. 4 is a top view thereof;
 FIG. 5 is a bottom view thereof;
 FIG. 6 is a right side view thereof;
 FIG. 7 is a left side view thereof;
 FIG. 8 is a back perspective view thereof;
 FIG. 9 is a front perspective view of a second embodiment of a mobile phone, showing our new design;
 FIG. 10 is a front view thereof;
 FIG. 11 is a back view thereof;
 FIG. 12 is a top view thereof;
 FIG. 13 is a bottom view thereof;
 FIG. 14 is a right side view thereof;
 FIG. 15 is a left side view thereof;
 FIG. 16 is a back perspective view thereof;
 FIG. 17 is a front perspective view of a third embodiment of a mobile phone, showing our new design;
 FIG. 18 is a front view thereof;
 FIG. 19 is a back view thereof;
 FIG. 20 is a top view thereof;
 FIG. 21 is a bottom view thereof;
 FIG. 22 is a right side view thereof;
 FIG. 23 is a left side view thereof;
 FIG. 24 is a back perspective view thereof;
 FIG. 25 is a front perspective view of a fourth embodiment of a mobile phone, showing our new design;
 FIG. 26 is a front view thereof;
 FIG. 27 is a back view thereof;
 FIG. 28 is a top view thereof;
 FIG. 29 is a bottom view thereof;
 FIG. 30 is a right side view thereof;
 FIG. 31 is a left side view thereof; and
 FIG. 32 is a back perspective view thereof.
 The broken lines in drawings show portions of the mobile phone that form no part of the claimed design in the embodiments in which they are shown.
